UNITED STATES PATENT OFFICE.

MARVIN H. BROWN, OF SAN FRANCISCO, CALIFORNIA, ASSIGNOR, BY DIRECT AND MESNE ASSIGNMENTS, TO H. J. McGINNIS, R. O'CONNOR, AND B. M. VIGOUREUX, ALL OF SAN FRANCISCO, CALIFORNIA, AND C. P. EGGLESTON, OF OAKLAND, CALIFORNIA.

INTERNAL-COMBUSTION ENGINE.

1,304,019.

Specification of Letters Patent. Patented May 20, 1919.

Application filed September 26, 1916. Serial No. 122,200.

To all whom it may concern:

Be it known that I, MARVIN H. BROWN, a citizen of the United States, and a resident of the city and county of San Francisco, State of California, have made a new and useful invention—to wit, an Improvement in Internal-Combustion Engines; and I do hereby declare the following to be a full, clear, concise, and exact description of the same.

The invention relates more particularly to the combination and arrangements of parts with the object of economizing the consumption of fuel by improving combustion and facilitating the starting of such motors. Other advantages will appear as the description progresses.

In this specification and the annexed drawings, the invention is illustrated in the form considered to be the best, but it is to be understood that the invention is not limited to such form because it may be embodied in other forms, and it is also to be understood that in and by the claims following the description it is desired to cover the invention in whatever form it may be embodied.

In the accompanying one sheet of drawing:

Figure 1 is a diagrammatic side elevation of an internal combustion motor and the fragmentary portion of an automobile body illustrating the application of this invention thereto.

Fig. 2 is an enlarged detail in side elevation partially in cross section of the agitating strainer forming part of this invention.

Fig. 3 is an enlarged fragmentary detail in side elevation of the sight feed and three-way valve combination.

Fig. 4 is a fragmentary enlarged detail of the three-way valve set in the water feeding position.

Fig. 5 is a similar view of the same set in the priming position.

Fig. 6 is a plan view from above of the agitator forming part of the strainer mechanism.

In detail the construction illustrated in the drawings includes the fuel tank 1, having fuel pipe 2 connected with the agitator 3 which is connected by the nipple 4 to the carbureter 5. The carbureter is fixed on the

in take manifold 6 which distributes the 55 gaseous fuel to the cylinders of the motor 7 in the usual manner. The carbureter may be of any conventional type, usually comprising a float chamber 8, within which the fuel is maintained at a constant level by an 60 automatic valve controlled by a float, the level of the fuel being adjusted with respect to a delivery nozzle projecting into the air passage for the purpose of carbureting air drawn through the air inlet 9, to form a 65 gaseous vapor to be drawn into the motor cylinders by the suction cycle therein.

In high grade volatile fuel, such as gasoline little difficulty is experienced in carbureting a mixture suitable for burning in the 70 cylinders of the motor. But even such high grade fuels as mentioned leave a residual deposit of carbon in the cylinders after combustion, indicating that combustion is not complete, and gradually lowering the efficiency of the motor as such deposits increase. Such deposits are prevented and eliminated when this invention is applied.

The present invention contemplates the use of kerosene, distillate and other low 80 grade hydro-carbon fuels. The agitator 3 (see Fig. 2) has an upper chamber 10 forming part of the fuel conduit separated from the lower chamber 11 by the screen or strainer 12. This strainer is mounted with 85 in a cage 13 having an annular flange 14 fitting snugly into an opening in the bottom of the chamber 10. This cage is provided with a base screwed into the bottom 14 of the chamber 11, being provided with 90 the wings 15 for convenience in inserting and unscrewing the base for the purpose of cleaning or repair. The drain cock 16 screwed into the bottom of the base provides a convenient means for draining off 95 water or other foreign accumulations in the fuel. The screen 12 is of a peculiar construction consisting of an annular wall fitting the case 13 to which it is soldered and through which all the fuel must pass to 100 enter the chamber 11 and flow onward through the nipple 4 to the carbureter.

This screen is made up of a continuous length of wire mesh having its inner end tapered to a point and coiled into a helix 105 or spiral 12'. This helix is kept in constant agitation by the vibration of the motor, which vibration is further accentuated by

the addition of the ball or weight 17, this agitation churns the fuel within the filter, and causes a freer flow of the fuel oil therethrough. From the agitator the fuel flows 5 through the nipple 4 to the carbureter wherein it is converted into a gaseous vapor by admixture with the air and is sucked into the cylinders of the motors and exploded or burned in the usual manner.

10 Water vapor is added to the carbureted mixture produced by the carbureter by being introduced into the manifold 6 at 18. The water contained in the tank 19 is drawn by the suction of the motor through the 15 conduit 20, through the sight feed 21, through the three way valve 22, into the tube 23 terminating in the manifold at 18. The volume of water thus drawn is controlled by the regulating needle valve 24, 20 operated by the knurled nut 25 in convenient reach of the operator. Attention is directed to Figs. 3, 4, and 5. In Fig. 4 the three-way valve is diagrammatically indicated in the open position to pass the 25 water through the sight feed and into the manifold at 18. It is desirable that the tank 19 be located below the level of the inlet 18 in the manifold, to prevent natural flowing of the water into the manifold when 30 the motor is not operating, thus rendering the admission of water to the motor automatic with its operation yet under mechanical control of the operator as to its volume. The suction in the manifold 6 35 varies with the speed of the motor, being stronger at low speed than at high, which results in a consequent variation in the supply of water to the opening at 18. At low speed the motor drawing the maximum 40 volume of water and at high speed diminishing proportionately. By introducing an aspirating opening at 26, I have provided an important feature. This hole 26 is directed toward the seat of the needle valve 45 24, and being located relatively close to the manifold 6, at which point the suction of the motor is greater, draws in a quantity of atmospheric air at high velocity which acts as an ejector in combination with the needle 50 valve to draw the water from the tank 19 and atomizes it into the sight feed 21, the atomized mixture of air and water passing into the manifold at 18 and combining with the carbureted fuel issuing from the carbureter. The combustion of this moistened 55 mixture within the cylinders insures perfect combustion and the elimination of all free carbon deposits within the engine cylinders, resulting in a fuel mixture that gives 60 off its heat slowly and expands throughout the piston stroke, resulting in the smooth, clean operation of the motor, in contradistinction to the higher grades of fuel which burn faster and result in a practical explosion 65 at the time of ignition, exerting a shock-

ing impulse upon the piston and connected mechanism, resulting in undue stresses and noise.

Even with the high grade gasoline fuel, internal combustion motors will not always 70 start readily and must under certain conditions be "primed" which is accomplished by injecting raw fuel in the manifold 6 by choking the air supply, or by introducing raw fuel directly into the cylinders through 75 priming cocks provided for that purpose. This is particularly true when such fuels as contemplated for use in connection with this invention are used. Practice has proven that low grade fuel, such as distillate and 80 kerosene are suitable for priming when introduced in the raw state into the cylinders, wherein they give off sufficient volatile gas to accomplish the first explosion when the engine is turned over. The resultant heat of 85 the first explosion accomplishing the volatilization of the next charge in that and the succeeding cylinders in the firing cycles. This priming is accomplished by the bypass pipe 27 connected into the fuel system at 90 the coupling 28 communicating with the upper chamber 10 of the agitator. In starting the motor the valve 22 is turned into the position shown in Fig. 5, in which the suction in the manifold 6 is communicated 95 through the pipe 23, through the valve 22, through the pipe 27 to the fuel line, drawing the fuel directly therefrom into the manifold 6, the quantity being regulated by the valve 22. When the engine starts, the 100 valve 22 is turned, feeding the fuel to the motor through its natural course through the carbureter, which is under control by a throttle in the usual manner. When the motor has warmed up to its proper capacity 105 running idle, the valve 22 can be turned into the position illustrated in Fig. 4, admitting the water mixture which brings the motor up to full capacity and ready to receive full duty load. Because of the great variety in 110 the design of internal combustion motors, carbureters and fuel systems, these elements have been diagrammatically illustrated in their simplest form, this invention being applicable to all types of motors in this class. 115

Having thus described my invention, what I claim and desire to secure by Letters Patent is:

1. The combination with the carbureter, the fuel supply pipe connected therewith and 120 the intake manifold in an internal combustion engine, a sight glass having an inlet through its upper end provided with an air intake and an outlet through its lower end, a three-way valve connected to the outlet of 125 the sight glass, a combined water and fuel pipe connecting one port of the valve to the manifold, a communicative connection between a second port of the valve and the fuel supply pipe, a water supply connected 130

to the inlet of the sight glass, and a valve in the upper end of the latter for controlling both the air and water intake, said three-way valve being operative to connect the first and 5 second ports or the first port and the sight glass.

2. In combination with an internal combustion motor, a water tank; a three-way valve having a sight feed thereon; a regulating valve controlling said sight feed; a conduit between said tank and the intake manifold of said motor through said regulating valve and said three-way valve and having an air hole therein, and a fuel supply pipe connected to the carbureter of said motor; and a by-pass leading from said fuel supply pipe through said three-way valve to said water conduit. 10

3. The combination with the fuel supply 20 pipe, the intake manifold and the interposed carbureter of an internal combustion engine, a water supply, a vertically disposed sight gage, a connection leading from the water supply through the upper portion of the 25 sight gage, a by-pass leading from the fuel

supply pipe, and valve means arranged in the outlet side of the sight gage and connected to the by-pass for shutting off the water supply and establishing communication between the by-pass and the manifold. 30

4. The combination with the fuel supply pipe, the intake manifold and the interposed carbureter of an internal combustion engine, a water supply, a sight gage having connection through its upper portion with the 35 water supply and provided with an air inlet in its upper portion for the entrance of air with the water, a by-pass leading from the fuel supply pipe, and valve means arranged in the outlet side of the sight gage and connected to the by-pass for shutting off the water supply and establishing communication 40 between the by-pass and the manifold.

In testimony whereof, I have hereunto set my hand at San Francisco, California, this 45 20th day of September, 1916.

MARVIN H. BROWN.
